UNITED STATES PATENT OFFICE

LOYD E. CARTMILL, OF SAN FRANCISCO, CALIFORNIA

REFRIGERATOR CAR

Application filed September 10, 1928. Serial No. 305,010.

This invention relates to refrigerator cars, and more particularly to the provision of insulation against external heat.

In order to maintain the cargo in a refrigerator car in good condition, care of course must be taken to keep the temperature therein at a proper low value. For this purpose, ice is quite often placed not only in the ice compartment, but also in the cargo compartment. Careful heat insulation is also essential in order that frequent icing be obviated.

It is one of the objects of my invention to provide an effective heat insulation for such cars, and especially for the floor thereof.

I have found that in order to obtain the full benefit of insulation for these purposes, the insulation layers, such as felted or cellular material, must be continuous and unbroken so far as possible; for if there be abutting edges of the layers, these layers, in stretching or contracting, may leave considerable areas unprotected against loss of refrigeration. It is accordingly another object of my invention to provide a continuous and unbroken series of insulation layers, and thereby to maintain the car interior at refrigerating temperature for a long period after each icing.

As mentioned before, it is now quite common to ice the cargo compartment of the car as well as the ice compartment, when the nature of the cargo carried so requires. It is another object of my invention to prevent injury to the car by the movement of the ice or cargo therein; and to ensure against the entrance of moisture between the floor layers.

My invention possesses many other advantages, and has other objects which may be made more easily apparent from a consideration of one embodiment of my invention. For this purpose I have shown a form in the drawings accompanying and forming part of the present specification. I shall now proceed to describe this form in detail, which illustrates the general principles of my invention; but it is to be understood that this detailed description is not to be taken in a limiting sense, since the scope of my invention is best defined by the appended claims.

50 Referring to the drawings:

Figure 1 is a fragmentary transverse section of the flooring through a refrigerator car embodying my invention; and

Fig. 2 is a fragmentary longitudinal section, taken adjacent the ice compartment of 55 the car.

In the present instance I show a refrigerator car having most of its substantial framework built in accordance with regular practice. Thus there are the side sills or beams 60 11, and a center beam 12. The outer walls of the car can be formed of a layer of wood 13, which may be tongued and grooved. This layer can be supported in any appropriate manner, which is not any part of the present 65 invention.

In order to form the floor of the car, I first of all place a layer of transverse boards 14 at the bottom, supported in any desired manner on the beams or sills 11, 12. For example, 70 the angle irons 15 fastened to beams 11 can be used to support the ends of these transverse boards.

Over this layer, I place one or more layers of heat insulation, that are of such size that 75 a single piece covers the entire floor area. Thus I show a layer 16 of felted or hair material, such for example as is known as "hair-insul". This is of such width and length that 80 all of its four edges can be turned up, as indicated in both Figs. 1 and 2. This layer can be held in place by transverse or longitudinal cleats 17, 18, 19, or by both transverse and longitudinal cleats. These cleats are shown 85 as slightly compressing this layer where they extend thereover, since hairinsul is non-rigid and readily compressible.

I show another layer 20 of insulation, also comprising a single piece of material, made 90 from some comparatively rigid cellular material, such as "celotex". This layer is fastened over the cleats 17, 18, 19, and there is accordingly, an air layer 21 between the two layers 95 of insulation. The comparatively rigid layer 20 then serves as a support for another layer 22, similar to layer 16. This layer also, is made from a single, unbroken sheet, the edges of which can be turned up. These turned up edges 23 effectively protect the corners of the 100 car against heat.

Above layer 22 is the tongue and groove flooring 24, which is spaced from the layer 22 to leave an intervening air space 25. This flooring extends across the width of the car and over the beams 11; it also extends longitudinally as far as the bearing rail 26 for the bulkhead separating the ice compartment from the cargo compartment. It is to be noted that this rail rests on the topmost layer of hairinsul 22, and does not interfere with its continuity.

The outer walls of the car also have insulation layers. Thus beneath the boards 13 there is a layer of hairinsul 27; then an air space formed between vertical posts 28, and then several layers 29 of insulation. At the side corners, I provide a mold 30 having a slightly overhanging edge 31 and a rounded interior corner 32. The inner wall lining 33 can be supported near its bottom edge on this mold 30. If desired, the conventional cargo racks 34 can be provided, hinged on appropriate hinge leaves 35. These leaves or supports have vertical extensions 41 that are disposed in recesses in lining 33. Bolts 42 serve to fasten the supports 35 to the wall. It is seen that the face of lining 33 extends beyond the end of bolt 42, so that no projections are present to injure the cargo when the cargo shifts. Furthermore, the hinge is at a considerable distance above the floor. When the rack 34 is raised on its hinge, it thus presents a large clear space for cleaning the floor or for inspection, removal or repairing of the floor covering material.

A continuous layer of waterproof felt paper 36 is attached or pasted over the flooring 24. This is carried up over the sides of molds 30 to protect the corners against moisture. Beading 37 holds the top edge of this layer in place on molds 30. Due to the fact that the inner lining 33 of the car extends beyond the corners, definite advantages are secured. First, sliding of ice or cargo against this layer cannot injure the corners; and second, whatever moisture collects on the car interior will drip down from the lower edge of lining 33, and cannot find its way beneath membrane or layer 36.

The waterproof felt paper 36 extends substantially the whole length of the car. As shown most clearly in Fig. 2, it passes over the edge of the drip pan 38 which is disposed at the bottom of the ice compartment, and which overlies the bulkhead rail 26, forming a continuation of the upper surface of flooring 24. The layer 36 in fact is preferably carried down over the inner edge of rail 26. A protection angle 39 of metal can be disposed over the layer 36; and the bulkhead (not shown) can be fastened to rail 26 in any desired fashion, as by bolts 40. It is apparent that the layer 36, protected by angle 39, and overlapping pan 38, will cause all moisture in the car to find its way into this pan,

and thence out through a conventional drain. Thus no moisture from melting ice in the cargo compartment can flow down into the flooring proper.

I claim:

1. A refrigerator car flooring having one or more layers of heat insulation, characterized by the fact that said layers of insulation are each a continuous and unbroken piece covering substantially entirely the whole floor area of the car, and having all of their edges turned up. 70

2. In a refrigerator car flooring, a supporting layer, one or more layers of insulation material disposed thereover, and cleats for holding and separating the layers, said layers being each formed of continuous material extending over substantially the entire floor area, and having upturned edges. 75

3. In a refrigerator car flooring, a layer of insulation made from cellular self-supporting material, and a pliant insulation layer supported directly thereon, and having its edges turned over. 80

4. In a refrigerator car structure, a floor, side walls, means for forming an inner lining for the walls, said lining projecting inwardly beyond the corner to prevent objects in the car from hitting the corner. 85

5. In a refrigerator car structure, a floor, side walls, a continuous waterproof layer for the floor extending part ways up the walls, and a lining for the walls projecting inwardly away from the waterproof layer on the walls, the bottom edge of said lining being thus spaced from the layer, to protect the corners and to prevent moisture collecting on the lining from entering back of the layer. 90

6. In a refrigerator car flooring structure, a flooring for the car, a bulkhead rail adjacent one end of the floor and assisting to define a cargo and an ice compartment, and a pan having an edge disposed over the rail, and a waterproof layer for the floor extending over the said edge and down into the pan. 95

7. In a refrigerator car flooring, a bulkhead rail adjacent one end of the floor and assisting to define a cargo and an ice compartment, flooring material extending adjacent the rail and forming the floor of the cargo compartment, and a waterproof layer on the floor and having an edge disposed over the rail. 100

8. In a refrigerator car flooring structure, a flooring for the car, a bulkhead rail adjacent one end of the floor and assisting to define a cargo and an ice compartment, a pan having an edge disposed over the rail, and a waterproof layer for the floor extending over the said edge and down into the pan, and a protecting metal angle disposed over the overlapping portion of the layer. 105

9. In a refrigerator car structure, means 110

5 forming a floor and side walls, a lining for the side walls, a floor rack disposed above the floor, and means for hinging the rack on the wall, said hinging means being supported on the wall in such manner that there are no projections beyond the lining surface.

10 10. In a refrigerator car structure, means forming a floor and side walls, a lining for the side walls, a floor rack disposed above the floor, and means for hinging the rack on the wall, including a hinge leaf, and means for so fastening the hinge leaf to the wall that the leaf does not project beyond the lining surface.

15 11. In a refrigerator car structure, means forming a floor and side walls, a floor rack disposed above the floor, and means for hinging the rack, said means being supported solely on the wall a substantial distance above the floor to permit raising the rack so as to gain ready access to the floor.

20 25 12. In a refrigerator car floor, a layer of wood, a non-rigid continuous insulation material thereon, having its edges turned up, a rigid layer of cellular insulation supported in spaced relation above said non-rigid insulation, a supplemental non-rigid layer of insulation directly supported on the rigid layer and having its edges turned up, and a wood flooring spaced above said supplemental non-rigid layer.

30 35 13. In a refrigerator car floor, a layer of wood, a non-rigid continuous insulation material thereon, having its edges turned up, a rigid layer of cellular insulation supported in spaced relation above said non-rigid insulation, a supplemental non-rigid layer of insulation directly supported on the rigid layer and having its edges turned up, a wood flooring spaced above said supplemental non-rigid layer, and waterproof material fastened to the wood flooring, having its edges turned up.

40 45 In testimony whereof I have hereunto set my hand.

LOYD E. CARTMILL.
